UNITED STATES PATENT OFFICE.

CHARLES O. HEGGEM, OF MASSILLON, OHIO.

DESIGN FOR A CYLINDER FOR STEAM-ENGINES.

SPECIFICATION forming part of Design No. 23,977, dated January 29, 1895.

Application filed October 29, 1894. Serial No. 527,347. Term of patent 7 years.

To all whom it may concern:

Be it known that I, CHARLES O. HEGGEM, a citizen of the United States, and a resident of Massillon, county of Stark, State of Ohio, have invented and produced a new Design for Steam-Engine Cylinders, of which the following is a full, clear, and exact description, reference being had to the accompanying drawing, making part of this specification.

The design relates to steam-engine cylinders, and their extended parts having the form and configuration shown in the accompanying drawing, wherein the design is represented in perspective.

The leading features of the design comprise the approximately rectangular frame A hav-

ing a marginal outwardly projecting flange or border, and a segmental extension B, the cylindrical part C having a segmental extension D, diverging arms E, and the cylindrical part F of greater diameter than the cylindrical part C and provided with the segmental extension G.

What I claim is—

The design for a steam engine cylinder as shown and described.

In testimony whereof I have hereunto set my hand this 23d day of October, A. D. 1894.

CHARLES O. HEGGEM.
